UNITED STATES PATENT OFFICE.

PETER J. HIEBERT, OF OKLAHOMA, OKLAHOMA.

THERMOSTATIC VALVE.

1,323,593.

Specification of Letters Patent.

Patented Dec. 2, 1919.

Application filed January 29, 1919. Serial No. 273,909.

To all whom it may concern:

Be it known that I, PETER J. HIEBERT, a citizen of the United States, residing at Oklahoma, in the county of Oklahoma and State of Oklahoma, have invented certain new and useful Improvements in Thermostatic Valves, of which the following is a specification.

This invention relates to thermostatically controlled valves.

The object of the invention is to provide a simple and efficient device for automatically cutting off the supply of gas should the burner be extinguished for any reason.

Another object is to provide a device of this character in which a thermostat is connected to automatically cut off a gas burner valve when the flame is extinguished, and which will hold the valve open as long as the flame remains lighted.

Another object is to so connect a thermostat and valve that they may be readily disconnected when it is desired to operate the valve by hand.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a side elevation of a gas bracket equipped with this improvement,

Fig. 2 is a similar view showing a slightly different form of the invention applied,

Fig. 3 is a similar view showing the invention applied to a valve for controlling the supply of gas to a plurality of burners, and

Fig. 4 is a side elevation showing a slightly different form of the invention.

In the embodiment illustrated, a gas bracket B of usual construction is shown, having a burner B' with a valve V for controlling the supply of gas to the burner. The valve V has an actuating arm 1 provided at its terminal with a finger 2 for a purpose presently to be described. A thermostat 3 in the form shown in Fig. 1, depends from the bracket B directly below the burner B' and its lower end is connected with one arm 10 of a bell crank lever 8, the

other arm 9 of which extends downwardly and is connected at its free end with a bar 5.

The bell crank 8 is shown fulcrumed on a bracket 11 which depends from the burner bracket B and may be secured thereto in any suitable manner.

The bar 5 has a loop 6 formed at its rear end and extending longitudinally thereof, the upper wall of said loop being provided with a plurality of ratchet teeth 7 with 65 which is designed to be engaged the finger 2 carried by the valve actuating arm 1. It will be seen by this connection that the bar 5 may be disconnected from the arm 1 at will, which is desirable when the valve arm 70 1 is to be actuated by hand.

From the above description it will be obvious that when the gas burner B' is lighted the heat emanating therefrom will expand the thermostat 3 as shown in full lines in 75 Fig. 1, thereby moving lever arm 10 downwardly and the arm 9 rearwardly carrying with it the control bar 5, which movement will open valve V and hold it open as long as the burner remains burning. Immediately the flame of the burner is extinguished, the thermostat 3 will contract or collapse, thereby exerting an upward pull on lever arm 10 and a forward pull on the bar 5, which will move the arm 1 forwardly into 85 the dotted line position shown in Fig. 1, and close valve V so that all danger of gas escaping from the burner will be prevented.

In the form shown in Fig. 2 the structure is the same except that the thermostat 3 is 90 carried by an arm 4 depending from the burner B' and the members of the thermostat are disposed vertically instead of horizontally as in the structure shown in Fig. 1. In this form the valve actuating bar 5 is 95 connected directly with the thermostat instead of through a bell crank. The operation, however, will be exactly the same as in the structure above described.

In the use of this device, the lever or arm 100 1 is first turned by hand into open position against the tension of the spring 1^a which exerts its tension to hold the valve normally closed and to return it to closed position after it has been opened. This valve after 105 being opened, and the burner B' lighted, will be held by hand until the thermostat 3 expands and then the arm may be released and said thermostat will hold the valve open as long as the burner remains lighted. As 110

soon as the burner is extinguished the thermostat will collapse and exert its contracting force to close the valve which is also assisted by the spring 1^a.

5 In the form shown in Fig. 3, the thermostat 3^a is suspended above a small gas burner b and is carried by a horizontal arm 12 of an upstanding bracket 13, said bracket being mounted on a gas pipe P. A valve V' is arranged between the burner b and the bracket 13 and has an actuating arm or lever 1^b. A bar 14 is connected at one end with the lever or arm 1^b and at its other end with the thermostat 3^a and is designed to open and close the valve on the expansion and contraction of the thermostat in the same manner as above described.

10 In the form shown in Fig. 4, the bracket B, burner B', valve V, thermostat 3, valve arm or lever 1, bracket 11, and bell crank 8 are the same as those shown in Fig. 1, the only difference being in the member 5' which connects levers 1 and 8. This member 5' in Fig. 4 is shown in the form of a spring bar 15 shown constructed of a coiled spring which operates to close valve V when the thermostat 3 contracts thus avoiding the necessity of using a spring on the valve. Moreover, when the tension of this spring is relaxed as 20 shown in full lines in Fig. 4 the lever 1 may be adjusted to regulate the flame in the usual manner.

25 From the foregoing description, taken in connection with the accompanying draw-

ings, the advantages of the construction and 35 of the method of operation will be readily apparent to those skilled in the art to which the invention appertains and while I have described the principle of operation of the invention together with the device which I 40 now consider to be the best embodiment thereof, I desire to have it understood that the device shown is merely illustrative and that such changes may be made as are within 45 the scope of the claimed invention.

Having thus fully described my invention, what I claim as new and desire to secure by Letters Patent, is:—

The combination with a gas burner having a supply control valve equipped with an 50 operating arm having a laterally extending finger, a thermostat positioned to receive heat from the burner when the latter is lighted, a bar connected with said thermostat and operable longitudinally on the expansion, 55 and contraction of the thermostat, said bar having at its free end an elongated longitudinally extending loop through which said finger projects, the upper wall of said loop having ratchet teeth for adjustable and detachable engagement by said finger.

60 In testimony whereof I affix my signature in presence of two witnesses.

PETER J. HIEBERT.
